SET-UP CONTAINER

Samuel N. Leopold and Henry K. Powell, Chicago, Ill., assignors, by mesne assignments, to President and Directors of the Manhattan Company, a corporation of New York, trustees for Gibson Patent Containers, Ltd., a corporation of New South Wales, Australia

Application November 29, 1932, Serial No. 644,809

22 Claims. (Cl. 229—5.7)

Our invention relates to containers for the packing or packaging of commodities, and pertains particularly to containers of the type which may be manufactured and shipped in a knocked-down or substantially flat condition and may be set up at the point of use. It finds particular utility in containers of substantial size, for example, containers of five-gallon capacity for the packaging of ice cream. The present application constitutes in part a composite continuation or division of our copending applications Serial No. 486,135, filed October 3, 1930, and Serial No. 503,019, filed December 17, 1930.

A general object of the invention is to provide an improved construction for a collapsible or knock-down container which may be made for the most part of paper board or the like, and which may be manufactured and shipped in a substantially flat knocked-down condition, and may be set up easily and quickly at the point of use to form a strong and accurately sized container which will suitably retain and protect its contents and which will be capable of withstanding the usage to which bulk packages of ice cream are subjected in transportation.

A particular object of the invention is the provision of an improved construction for such a container which is particularly adapted for the freezing within it of a content of ice cream or other material which expands upon freezing, the container being qualified to accommodate expansion of its contents, and the joints or connections between the separately formed portions of the container being tightened and rendered additionally secure incident to the expansion of the contents.

Another object of the invention is the provision of a container of the type above specified which is particularly qualified for use as a dispensing container, for example, for the retention of ice cream or other frozen commodities in the refrigerating well of a cabinet and the piece-meal removal of the contents from time to time.

Another object is the provision of a container of the type above specified which is particularly well qualified for the stacking of one upon another, as in a freezing room for the freezing of the contents, and capable of withstanding the considerable weight which may thus be imposed upon it.

Still another object is the provision of an improved container construction of the type above specified in which the margins of the several connected parts, and the joints between the parts,

are dimensioned to provide a certain amount of slack space for fitting their various parts together, and the slack is to furnish sufficient room for the introduction of a filling or dispensing tool.

Other objects and features of the invention will be apparent from a study of the following detailed description of the preferred embodiment.

Reference is had to the drawings which are a part of this specification and which illustrate the invention.

Fig. 1 represents a view of a sheet of suitable

material as formed for the body member of a

container;

Fig. 2 is a cross section of a portion of such

a sheet, on an enlarged scale;

Fig. 3 is a similar cross section illustrating a

portion of such a sheet when flexed to a bowed

form;

Fig. 4 is a diagram illustrating an operation

which may be employed in the forming of the

sheet for the body member;

Fig. 5 is a perspective view of the completed

body member in its knocked-down or flat folded

form;

Fig. 6 is a broken-out sectional elevation of a

set-up container;

Fig. 7 is a broken-out sectional elevation of a

portion of the container illustrating the relation-

ship of the body member and top closure after the

latter has been somewhat expanded by its con-

tents;

Fig. 8 is a fragmentary detail, partly in side

elevation and partly in sectional elevation, of an-

other form of constraining member;

trating relationship of certain parts incident to

the assembling of the body member and an end

closure.

The provision of an effective container which

may be manufactured and shipped in collapsed or substantially flat knocked-down form and may be set up with facility at the point of use attains numerous important commercial advantages.

5 The provision of an effective container of such a character presents several difficult problems, particularly when it is desired that the container be of comparatively light weight, yet have substantial capacity, appropriate for the commercial 10 packaging of materials in bulk, and possess quite substantial strength.

The requirements which such a container must meet in various uses, such, for example, as for the 15 commercial packaging of ice cream or other frozen commodities in bulk, present additional problems. In the case of ice cream packing, for instance, it is a customary practice of ice cream manufacturers to fill the containers, in which the product is distributed to the trade, with 20 the ice cream mixture in a fluid, partly frozen, condition, apply the closure to the container, and then freeze the contents in the container. Such freezing is ordinarily done in a freezing room, the containers being stacked one upon another. As 25 an incident of the freezing, the contents of the container expands very considerably in volume. Ordinarily, the containers so used are of five-gallon or two-and-one-half-gallon capacity, and, after freezing, the packages are delivered 30 unopened to the trade, and the packages are placed by the dealers in refrigerating cabinets where, after the package is opened, the contents are dispensed or dished out piecemeal from the original container in the making of individual sales. It 35 will be apparent that such usage requires a container which, in addition to being quite tight, must be of very substantial strength and quite accurately sized.

The present invention provides a container 40 which meets these requirements and attains the numerous advantages of a structure which may be supplied to the user in knocked-down condition, set up by him with facility, and which may be supplied at a cost sufficiently low to justify its 45 being discarded after being once used.

The nature of the invention will be ascertained most quickly upon an understanding of the illustrative examples shown in the drawings, which will now be described.

50 The container comprises a body member which is tubular when set up, and suitable end closures. The body member is made of flexible material possessing the requisite toughness and rigidity for the intended use. For an ice cream container of five-gallon capacity, for example, the material 55 may be a suitable paper board approximating .045 inch in thickness. In Fig. 2 is represented a cross section of such a board, of laminated structure, comprising a chip center portion 16, liner 11 and craft outer sheet 12, all secured together by a suitable adhesive as in customary converting practice. It will be appreciated that the board need not necessarily be of this particular structure, or 60 that it be of laminated structure.

65 In forming the body member, it is provided along its lower margin with a series of tongues 14, between which the material is slotted, as at 15, for a short distance. The body member is formed 70 with flexing creases or slightly offset portions 18 extending in the longitudinal, or top-to-bottom, direction and spaced from one another by appropriate intervals. In this creasing or offsetting of the board, the material is not distorted to an extent such as to shear or break the fibers, but the

offset is sufficient to striate the board by forming shallow grooves on one side thereof and low ridges on the other. It will be understood that these creases or offsets may be pressed in the board in various fashions and in various forms, and as seen in Fig. 1, their arrangement is such that some of them are staggered or offset laterally relative to the tongues, thereby placing one of them opposite each of the spaces between the tongues. The body member 10 is also creased to provide fold lines 17 on which its opposite portions may be folded into collapsed relationship, as illustrated in Fig. 5. Along the upper margin of the body member, on what is to be the outer side of the container, is secured a 15 strip 13 which forms an outwardly extending rim. This strip may be creased transversely in the same fashion as the body member.

The flexing creases or offset portions 16 facilitate the shaping or conformation of the body member to the desired form or contour when set up, and in order to further this effect, the board may be subjected to a bending operation as illustrated in Fig. 4, by being passed through a flexing machine which bends the board around axes parallel to the creases 16. This flexing has the effect of somewhat loosening the fibers at the creased or offset portions, without appreciably decreasing the top-to-bottom stiffness of the board, and thus renders it somewhat more flexible at the creased portions. An application of suitable water-proofing material, such as paraffin, is made to the surfaces of the board, the same being substantially ironed in so as to avoid any appreciable coating which might be scraped off. The board is formed into a continuous body member, as by convention of its meeting portions by staples 18 or otherwise, and is collapsed by bending it on the fold lines 17. The body member is thus produced in a collapsed or knocked-down form in which it 40 may be shipped and from which it may be set up in tubular form.

For assembly with the body member, there is provided a relatively non-distensible constraining member 20 of annular form and of slightly 45 greater circumference than the body member. This constraining member has an annular portion 20^a adapted to extend across the end margin of the body member when it is set up in the desired tubular form, and an inwardly extending portion 50 20^b which is adapted to encompass the end portion of the tubular body member peripherally. A disk 21 of stiff paper board fits within the constraining member in contact with the portion 20^a thereof. A disk 22 of stiff paper board is also provided, conforming in contour to the desired contour of the body member, but of a diameter somewhat exceeding the contemplated internal diameter thereof. A second relatively non-distensible 55 constraining member 24, of the desired circumferential contour of the body member, is provided for cooperation with the other end of the latter. This second constraining member has an annular portion 24^a of somewhat greater internal diameter 60 than the contemplated diameter of the set-up body member, and adapted to encompass the upper end portion of the latter peripherally. At the upper end of the portion 24 is an inwardly extending bead 24^b and at its lower end an inwardly 65 extending flange 24^c, the flange 24^c being of such width that the constraining member may be slipped into encompassing relationship on the body member, and the bead 24^b preferably being 70 75

of somewhat greater width so as to extend farther toward the axis of the body member. An end closure disk 25, of stiff paper board, is positioned within the constraining member 24, where its 5 margins are overlapped by the bead 24^b.

In assembling the container from the flat or knocked-down condition, the collapsed body member is opened to a tubular form and the tongues 14 are bent inwardly. The tongued end 10 of the body member is then inserted in the constraining member 20, making a close fit with the upper margin of the portion 20^b, whereby it is constrained in the desired circumferential contour. The inwardly folded tongues rest flat upon the 15 end disk 21, and the intervening slots 15 are of such length that they extend to a point just short of the upper margin of the portion 20^b. The disk 22 is then inserted edgewise into the body member through its upper end, and, in sloping position, 20 into engagement with a portion of the body member that is within the portion 20^b, and then pressed down into flat position against the tongues 14. The disk 22 being oversize, the forcing of it to this 25 position forces the slotted end portion of the body member outwardly under the overhanging or inwardly extending portion 20^b of the constraining member, thus locking the body member and the disks 21 and 22 and constraining member 20 together.

30 With the body member and container bottom thus assembled, the former is held in its tubular form, and the receptacle thus provided is adapted to stand upright on its bottom, so that it may be readily filled with the material which is to be 35 packaged in it. After the contents are placed in the receptacle, the top closure, comprising the constraining member 24 and disk 25, may be applied to it. The disk 25 being disposed in the constraining member 24, as above described, said disk 40 being of such size as to overlap the top edge of the body member, the constraining member is slipped onto the upper end of the body member so that its annular band 24^a encompasses the upper end of the body member peripherally and 45 the disk 25 seats upon the upper edge of the body member so as to close its top opening. When seated, the inwardly projecting flange 24^c will occupy a position below the lower margin of the retaining strip 13, and the bead 24^b, in its 50 overlapping relationship to the margin of the disk 25, will hold the latter against withdrawal upwardly. Due to the transverse flexibility of the body member, portions of the retaining strip 13 will project over the flange 24^c and serve to retain 55 the constraining member and disk 25 against removal readily from the body member.

Assuming that the commodity packed in the 60 container is to be ice cream or some other material which is to be frozen, and which expands on freezing, the closed package may be submitted to freezing treatment, as in a freezing room. With the expansion of the contents resulting from the freezing, outward pressure will be exerted upon the body member, and this will have the 65 effect of distending the latter, as is illustrated in somewhat exaggerated degree in Fig. 7. Such distention is accommodated or facilitated by the pliability of its material and by the character of the creasing, the material in the striae or offset 70 portions 16 being susceptible of displacement radially as the body member is drawn taut in approximately circular peripheral contour. Such distention of the body member is also accommodated, in some measure by its form. As pointed 75 out above, the body member wall is relatively more

flexible at the creased portions 16 than in the intervening portions, and as a result, in the setting up of the body member in tubular form, greater flexion may take place at the creases than in the intervening wall portions and the latter 5 may not be fully arched out to a uniform radial distance from the axis of the container. As a consequence, they will accommodate an appreciable increase in the capacity of the container when arched out into approximately circular peripheral 10 contour.

The portions of the body member which are encompassed by the relatively non-distensible parts 20^a and 24^a of the constraining members are susceptible of distention in the manner above 15 explained, with the result that when so distended by the pressure of the container's contents, they will be pressed into very close binding engagement with said portions of the constraining members. Thus the lower end portion of the body 20 member will be further distended into the recess under the inwardly extending portion 20^a of the lower constraining member, the lower end of the body member being susceptible of such distention due to the fact that the tongues 14 are not fixedly 25 secured to the bottom closure, but may slide outwardly between the disks 21 and 22. The portion of the body member encompassed by the upper constraining member 24 may likewise be distended into the internal recess afforded between the 30 bead 24^a and flange 24^c, so that the latter will grip the body member peripherally and engage definitely below the outwardly extending retaining strip 13. This relationship is illustrated in 35 Fig. 7. The portions of the body member intermediate the two constraining members may be distended appreciably beyond the inner margins of the flanges 24^c and 20^b.

The distensible character of the body member thus not only accommodates the expansion of the 40 container's contents, in such fashion that the end closures will not be forced off, but also contributes to a more secure connection of the body member and the end closures.

An alternative form for the constraining member 24 is illustrated in Fig. 8, wherein said member, instead of being provided with an inwardly extending flange at its lower margin, is provided with the inwardly punched burrs 24^d which are pressed into the body member peripherally upon 50 its distention as above described, thus to retain the constraining member securely in place thereon.

A further alternative construction, which may be employed for the bottom constraining member, is illustrated in Fig. 10, wherein the constraining member is designated by the reference character 38 and has an inwardly extending bead 39 at the margin of its body-encompassing portion, adapted to exert binding constriction on the 60 distended body member and to engage and co-operate with a retaining strip 37 which is secured to and projects peripherally from the body member. The constraining member has the inwardly extending annular flange 41 adapted to overlap the marginal portion of the paper board insert disk 40, which disk is preferably of such size as to expand the lower end of the body member somewhat when the disk is forced to normal position therein, and hold it in close engagement with the 65 encompassing constraining member.

As has been indicated above, the constraining members are relatively non-distensible, which characteristic may be attained by forming them as continuous members of strong sheet metal. 75

In addition to their functioning as constraining members to hold the parts in assembled relationship as above described, they constitute effective enveloping reinforcements for the edges of the container as well as stable elements holding it in shape. Consequently, the filled container may be rolled along on its lower peripheral edge without crushing or distorting the relatively fragile margins of the body member or closure disks, and these margins and the joints between them are guarded by the enveloping constraining member against wetting and consequent softening when the container is set on a damp floor. It will be observed also that the construction provides a container with substantially flush ends. This feature is of value, not only in guarding the ends of the body member and the end closures against distortion, but also in facilitating the stacking of the filled and closed containers, one upon another, and enabling them to withstand the loading pressures resulting from such superimposed weight.

It will be apparent that various changes may be made in the particulars or details of construction above described without departing from the spirit and characterizing features of our invention.

What we claim is:

1. In an ice cream can, a tubular body member formed of paper board and being provided with a plurality of spaced fold line creases permitting said body to be collapsed to substantially flat condition, said body member also being provided intermediate said fold line creases with a plurality of axially extending, body-softening creases for facilitating distention and bending of the body intermediate said fold line creases, said intermediate creases being so formed as to maintain substantially full thickness of the body blank in the areas of said creases and so as to be so shallow as to constitute negligible irregularities in the normal smoothness of the body wall.

2. A container comprising a tubular body member of paper board material, relatively non-distensible constraining members encompassing said tubular body member circumferentially adjacent its ends, and closures for the ends of the tubular body member retained by said constraining members, portions of said body member encompassed by the constraining members being formed with narrow radially offset parts to permit circumferential distention of said portions by pressure from the container's contents and effect close binding engagement of said portions against the constraining members.

3. A container comprising an integral, longitudinally creased, circumferentially distensible tubular body portion, relatively annular constraining members interlocked with the body member and encompassing it circumferentially adjacent its ends and bearing against its peripheral surface between the creases, and closure members for the ends of the tubular body member retained by said constraining members.

4. A container as specified in claim 3 and wherein the body member and closure members are made of paper board and the constraining members of metal, and the constraining members are shaped to form a shrouding covering and confining the ends of the body member and the peripheries of the closure members.

5. A container structure comprising a body member of paper board material formed to permit its being collapsed to flat folded form and adapted to be set up in tubular form, said body member being provided with a plurality of narrow axially extending inwardly offset portions

facilitating its being distended circumferentially in tubular form, relatively non-distensible constraining members adapted to telescope onto end portions of the body member and bear against the peripheral surface thereof to limit circumferential distention of said end portions, and disks retained by said constraining members to constitute end closures for the tubular body member.

6. A container structure as specified in claim 5 and wherein the body member and constraining members have portions adapted to interengage to retain the constraining members against endwise withdrawal from the tubular body member.

7. In a container, in combination, a body member of paper board adapted to be folded to collapsed flat form and to be set up in tubular form, said body member being creased in axial direction to provide in it a plurality of narrow offset portions which are spaced laterally from one another and are offset from the normal surface of the sheet to an extent less than the sheet's thickness, whereby the body member is rendered additionally flexible into its tubular form, a relatively non-distensible constraining member of annular form applicable to the body member to encompass an end portion thereof circumferentially when it is set up in tubular form, said constraining member being of such diameter as to limit distention of the portion of the body member encompassed by it, and a closure member adapted to be retained by the constraining member in closing relationship to the end of the body member.

8. A container comprising, in combination, an integral body member of flexible paper board material formed to fold into collapsed form and to be set up in tubular form, said body member having its walls formed with a multiplicity of narrow inwardly offset areas extending longitudinally thereof and spaced apart from one another circumferentially thereof and being more readily flexible about the axis of the body member at said areas than in the areas therebetween so as to facilitate bending of the body to predetermined tubular form, and a relatively rigid constraining member for encompassing the body member peripherally and supporting it in said predetermined tubular form.

9. A container comprising, in combination, an integral body member of flexible paper board material formed to fold into flattened collapsed form and to be set up in tubular form, said body member having its walls formed with a multiplicity of circumferentially-spaced longitudinally-extending narrow areas in which the material is slightly offset inwardly to facilitate the flexing of the body member about its axis, a relatively rigid annular constraining member formed to encompass the body member peripherally and bear against its outer surface between said narrow areas, thereby to sustain it in its tubular form, and an end closure retentively engaged by said constraining member.

10. In a container of the class described, the combination of a collapsible tubular paper board body having a shoulder adjacent to its lower end, a separate bottom member, and means seated on said shoulder for mounting said bottom member within said body with the bottom surface of the bottom member substantially flush with the bottom end of the body, said means comprising an annular member having a side portion fitting the lower portion of said body and having a rim portion overhanging said shoulder and a bottom flange extending inwardly substantially in the

plane of the bottom end of said body for receiving and supporting said bottom member.

11. In a container of the class described, the combination of a collapsible tubular paper board body having an external shoulder at its lower end, a separate bottom member, and means seated on said shoulder for mounting said bottom on said body substantially flush with the bottom end of the latter, said means comprising a metallic annular member having a side portion encompassing the lower marginal portion of said body and having a rim portion overhanging said shoulder and a stiff annular bottom flange extending inwardly across and in contact with the lower margin of the body, for preventing downward displacement of the bottom member from the body.

12. In a collapsible container of the class described, the combination of a tubular body member of paper board, said body having fold lines facilitating the collapsing of the body to substantially flat condition, and an end closure for one end of said tubular body including an annular metallic member fitting the end of the body so as to protect and reinforce the same, said metallic member including a side portion encompassing the end portion of the tubular body and a stiff annular end flange projecting laterally inwardly from one end of said side portion across the end margin of the body, interlocking means carried by said body and metallic member for anchoring the latter against removal endwise from the body, and an end closure disc of paper board fitting inside of said body and having a marginal portion resting upon said end flange.

13. A container for ice cream or the like, comprising a tubular body formed of fibrous sheet material and provided with a plurality of longitudinal creases which offset narrow portions of the body inwardly so as to contract its circumferential size somewhat and permit circumferential expansion thereof by outward pressure, and an oversize disk insertable into an end portion of the body member to hold it expanded in approximately circular form.

14. A set-up container comprising in combination, a tubular body member of fibrous sheet material susceptible of being collapsed to flat folded form, said body member being creased from top to bottom at close intervals to facilitate its taking an approximately cylindrical form, a stiff annular constraining member formed to encompass an end portion of the tubular body member and bear upon its peripheral surface between the creases, and a disc member inserted in the body member within the compass of the constraining member and cooperating therewith to hold the end portion of the body member in approximately circular form.

15. A container comprising a collapsible tubular body member formed of flexible paper board and having a shoulder projecting from the outer side thereof, an annular non-distensible rim encompassing said body member and having a pre-formed lip extending inwardly over said shoulder and a rigidly supported annular flange extending inwardly across the end of the body member, and a separate end disk supported on said annular flange and engaging the inner surface of the body member to hold said shoulder outwardly under said lip.

16. A knock-down container comprising a collapsible tubular body member formed of flexible paper board and having an outwardly projecting ledge adjacent an end thereof, an end disk formed to fit within said end of the body member and

maintain it in annular form, and a pre-formed metallic rim shaped to encompass said end of the body member and having a lip extending inwardly to overlap said ledge and an annular flange extending inwardly for supporting engagement with the end disk.

17. A knocked-down container comprising a tubular body member formed of a normally inextensible material and provided with a plurality of longitudinal fold creases and interposed parallel flexing creases which permit diametric collapsing and expansion thereof, and a relatively non-distensible constraining member adapted to telescope onto and interengage with the body member in encompassing relationship to an end portion thereof so as to bear against its peripheral surface intermediate said creases, and an end closure retained by said constraining member to form an end closure for the tubular body member.

18. In a container, a tubular container body formed of paper board and provided with a plurality of circumferentially spaced longitudinally extending shallow striae which permit diametric collapsing and expansion of the body member, and a relatively non-distensible constraining member retentively engaged with and encompassing an end portion of the body member and bearing against the peripheral surface thereof between said striae, and an end closure retained by said constraining member in closing association with said end of the body member.

19. In a knock-down container, the combination of a collapsible tubular body member made of paper board and having an end formed to provide a row of narrow longitudinally extending flexible tongues and a wall portion provided with a plurality of longitudinally extending creases arranged in staggered relationship with the several tongues, said creases being formed and arranged to facilitate flexing of the body member to approximately cylindrical tubular form and permit bending of the tongues into radial disposal, and an end closure adapted for retentive engagement with the body member at said end to hold the end of the wall portion in approximately circular form.

20. In a knock-down container, the combination of a collapsible tubular body member made of paper board and having an end formed to provide a row of narrow longitudinally extending flexible tongues and a wall portion provided with a plurality of longitudinally extending creases arranged in staggered relationship with the several tongues, said creases being formed and arranged to facilitate flexing of the body member to approximately cylindrical tubular form and permit bending of the tongues into radial disposal, and separate end closures adapted to interlock with respective ends of the body member and hold the wall portion in approximately cylindrical tubular form.

21. In a knock-down container, the combination of a collapsible tubular body member made of paper board and having an end formed to provide a row of narrow longitudinally extending flexible tongues and a wall portion provided with a plurality of longitudinally extending creases arranged in staggered relationship with the several tongues, said creases being formed and arranged to facilitate flexing of the body member to a rounded tubular form and permit bending of the tongues into angular relationship to the wall portion, and an end closure adapted for retentive engagement with the body member at said end to hold the end of the wall portion in rounded form.

22. In a knock-down container, the combination of a collapsible tubular body member made of paper board and provided with a series of longitudinally extending creases spaced laterally from one another, said body member having an end portion slit at short intervals in alignment with a plurality of the creases to form a plurality of narrow longitudinally extending tongues, said creases being formed and arranged to facilitate

flexing of the body member to a rounded tubular form and to permit bending of the tongues into angular relationship to the wall portion, and an end closure adapted to interlock with said end portion of the body member and hold the end of the wall portion in rounded form.
